APPARATUS FOR INTRODUCING HIGH VOLTAGES INTO CONTAINERS

**Delber W. Turner, Houston, Tex., assignor to
Petrolite Corporation, Ltd., Wilmington, Del.,
a corporation of Delaware**

Application March 23, 1945, Serial No. 584,433

16 Claims. (Cl. 200—52)

11

My invention relates to structures for introducing high voltages into a container and, more particularly, to an arrangement facilitating replacement of a bushing used for this purpose.

It is often necessary to introduce high voltage currents into a container filled with a fluid which may be at superatmospheric or subatmospheric pressure. An inlet bushing is conventionally employed, having a conductor through which the high voltage currents enter the container to energize suitable equipment disposed therein. Such an inlet bushing sometimes fails in operation, either because of electrical breakdown or mechanical defects. To effect replacement, it has heretofore been necessary to equalize any pressure differential between the inside and outside of the container, if such pressure differential exists; to expose the contents of the container to the atmosphere; or to remove such contents

Such difficulties are particularly apparent when the container is filled with inflammable liquid under high pressure, and the invention will be particularly exemplified as applied to electric treaters employed in the petroleum industry for electrically resolving emulsions, though it should be clear that the invention is not limited thereto.

be clear that the invention is not limited thereto. Such electric treaters provide a container, often filled with hot oil under pressure, and providing one or more electrodes to which a high potential is applied by use of an inlet bushing. Heretofore, removal of the bushing for inspection or replacement has necessitated relief of any superatmospheric pressure on the oil, drainage of the oil from the container, and, often, steaming out the container before the bushing can be removed with safety. This procedure is particularly objectionable in large-sized installations especially when the unit is installed in close proximity to, and operating in conjunction with, a refinery where the charging stream for the refinery passes through the unit. It is essential to shorten as much as possible the time period required for change in bushings and, by the present invention, a bushing change can be made in a few minutes instead of a few hours.

It is an object of the present invention to provide a novel arrangement whereby a bushing conducting electrical potentials into a container can be removed without opening the container, exposing its contents to the atmosphere, relieving any pressure differential across the container, or draining the container.

It is a further object of the invention to provide a conducting member within the container and movable into and out of electrical contact with

the conductor of the bushing. In the preferred embodiment of the invention, such movement is effected from a position outside the container.

5 It is a further object of the invention to provide a movable insulator within a container, this insulator carrying a conducting member which is movable into and out of electrical contact with the conductor of an inlet bushing.

Still a further object of the invention lies in a structure wherein a valve or other closure is provided near the zone of electrical contact between such a conducting member and a conductor of a bushing, whereby separation of these elements permits closing the valve or closure preparatory to removal of the bushing.

Additional objects of the invention lie in the provision of a novel structure for effecting and guiding the movement of a conducting member into and out of electrical contact with the con-

20 ductor of an inlet bushing.
Further objects and advantages of the invention will be evident to those skilled in the art from the following description of an exemplary embodiment.

25 Referring to the drawing:

Fig. 1 is a vertical sectional view showing diagrammatically one manner of employing the invention in the upper end of a container.

Fig. 2 is an enlarged sectional view, taken along the line 2—2 of Fig. 1:

Fig. 3 is an enlarged vertical sectional view of the insulator support or control unit shown in Fig. 1.

Fig. 4 is an enlarged view, partially in section, of the resilient contactor shown in Fig. 2; and Fig. 5 is a fragmentary sectional view, taken as indicated by the line 5-5 of Fig. 3.

Referring particularly to Fig. 1, the exemplified electric treater provides a spherical container 10, only the upper portion of the wall thereof being shown, this upper wall being indicated by the numeral 11. Mounted within and extending across the upper end of the container 10 is a

framework 12 comprising spaced members 13
45 traversed by cross members 14, the ends of these
members being suitably attached to the container
and being at the ground potential of the con-
tainer. Suspended from suitable insulators is an
electrode structure, the details of which need not
50 be specifically enumerated as they are shown in
the copending application of Logan C. Waterman
and Gordon B. Hanson, Serial No. 326,274, filed
March 27, 1940. Suffice it to say that this elec-
trode structure may include an upper electrode
55 20 comprising a suitable frame 21 from which

depends a plurality of concentric rings 22, and a similar lower electrode 25 having a suitable frame 26 on which is mounted a plurality of concentric rings 27. These electrodes are insulated from each other by the supporting insulators to be described, and are spaced apart to define a treating space 28 into which the incoming emulsion discharges radially through a distributor 29.

The frame 21 of the upper electrode is usually supported by three strings of suspension insulators connected by rods 32 to the frame 21. For purpose of clarity, only one suspension insulator is shown in Fig. 1, being indicated by the numeral 33, it being understood that additional suspension insulators are employed to give a three-point support for the upper electrode. The upper end of each of the suspension insulators is connected to the framework 12. Similarly, the lower electrode 25 is supported at three points by three additional suspension insulators, one being indicated by the numeral 35, rods 36 being connected to the frame 26 to serve as hangers for the lower electrode.

Fig. 1 shows two bushing-changing systems of the invention through which the electrodes 20 and 21 are respectively energized to develop a high voltage field in the treating space 28. The high voltage source is diagrammatically shown as comprising transformers 40 and 41 with secondary windings connected additively, the common terminal being grounded, as indicated, and the high voltage terminals supplying the high potentials through bushings 42 and 43 to the electrodes, maintaining each electrode at above-ground potential. Only one bushing-changing arrangement of the invention will be described in detail as the other is a duplicate.

As best shown in Figs. 1 and 2, a tubular structure 50 extends upward from the wall 11 and provides a passage 51 opening on the interior of the container. As shown, the tubular structure comprises a lower flanged tubular member 52 welded at 53 to the wall 11, and an upper double-flanged tubular member 55 between which is bolted the body of a gate valve 57, serving as one embodiment of a closure means for the passage 51. This gate valve is shown diagrammatically as including a closure member or gate 58 slidable in a tapered passage 59 under the action of a hand wheel 60 to close off completely any communication between the upper and lower portions of the passage 51, as will be later described. If desired, the tubular member 55 may provide an opening 61, shown as closed by a plug 62, for admitting liquid or gas to the upper portion of the passage 51.

The bushing 42 may be of any desired construction and carries a conductor 64. Suitable means is provided for removably connecting the bushing 42 to the tubular structure 50. As shown, this means includes an adapter flange 65 to which a flared portion 66 of the bushing is connected in any suitable way.

The lower end of the conductor 64 comprises or carries a resilient contactor, indicated generally by the numeral 67, the details of which are best shown in Fig. 4. Referring thereto, this resilient contactor comprises an upper or support member 68 having a neck 69 threaded to the lower end of the conductor 64 and secured thereto, as by a set screw 70. It includes, also, a contact member 71 and an intervening spring 72 having its ends respectively connected to the members 68 and 71 by clips 73 and 74. This spring forms a resilient mount for the contact member 71.

Preferably the downward movement of the contact member 71 is limited by auxiliary connecting means extending between the members 68 and 71, this means preferably comprising three flexible members 75, each secured at its ends to brackets 76 attached respectively to the members 68 and 71. Such auxiliary connecting means serve the dual function of insuring good electrical conductivity between the members 68 and 71 and also to maximize the spacing thereof under the action of the spring 72 by becoming taut when the spacing is approximately as shown in Fig. 4. At the same time, it will be clear that the contact member 71 can be moved upward a distance under the action of any upward pressure applied thereto, the spring 72 compressing to permit this movement and the flexible members 75 flexing within the confines of the spring 72. Such upward movement of the contact member 71 may take place through the action of the conducting member to be later described. The lowermost position of the contact member 71 should be above the closure for the passage 51 provided by the gate 58 of the valve 57.

Associated with the tubular structure 50 is a control unit, indicated generally by the numeral 80 and best shown in detail in Fig. 3. This control unit includes a pipe 81 extending through the wall 11 to one side of the tubular structure 50. The pipe carries a flange 82 at its lower end inside the container 10 and is welded to a flange 83 outside the container. Bolted to the flange 83 is a sealing means comprising a packing gland structure 84 through which extends a vertically movable operating member 85. A packing 86 journals and seals the operating member 85 and is compressed by a packing gland 87, best shown in Figs. 3 and 5. Extending upward from the packing gland structure 84 on opposite sides of the operating member 85 are posts 88 carrying a yoke 89 at their upper ends. A nut 90 is journaled in this yoke and is connected to a hand wheel 91 by a tapered connection tightened by a nut 92. During its rotation, the nut 90 is restrained from vertical movement relative to the yoke 89 by the hand wheel 91 and by a lower flange 93 engaging the yoke 89. The nut 90 rotates relative to the threaded upper end of the operating member 85. Turning of the hand wheel 91 will thus raise and lower the operating member. The uppermost position of the operating member, shown in Fig. 3, is determined by lock nuts 95 which come into engagement with the flange 83. The lowermost position of the operating member is determined by lock nuts 96, acting as a stop means when they are lowered to engage the upper end of the nut 90.

The operating member 85 extends into the interior of the container 10 and is journaled near its lower end by sliding through the opening of a plate 97 bolted to the flange 82. Means is preferably provided to prevent turning of the operating member 85 about its axis as it is raised and lowered. To accomplish this, a stationary guide 100 is provided within the container and to one side of the axis of the operating member. This guide is formed by a rod bent into U shape and having its ends welded to the plate 97 to form two rod members having outwardly-extending portions 101 and depending portions 102, the latter being spaced from each other to provide a guide passage 103. Near the lower end of the operating member 85 is secured a collar 104 carrying a sidewardly-extending guide member 105. This guide member extends into, and is

vertically slidable along, the guide passage 103.

Carried by the lower end of the operating member 85 and vertically movable therewith is a suspension insulator 110, usually comprising a string of petticoat-type insulators connected together to prevent relative rotation therebetween. This suspension insulator moves up and down with the operating member 85 and is prevented from turning by the inter-engagement of the stationary guide 100 and the guide member 105.

Carried by the lower end of the suspension insulator 110, and insulated from the container 19 thereby, is a conducting member, generally indicated by the numeral 111. This conducting member preferably includes an arm 112 extending sideward from the axis of the insulator 110 and a vertically-extending contact portion 113, the upper end of which is vertically movable in the passage 51 of the tubular structure 50 to move into and from electrical contact with the conductor 64 of the bushing. The electrical contact is preferably made through the resilient contactor 67 and by use of a cup-like contact member 115 attached to the extreme upper end of the conducting member 111 to move into and from engagement with the contact member 71 of the resilient contactor 67. The contact member 115 may be beveled to provide a relatively sharp lip engaging the lower surface of the contact member 71, and the latter member may provide a centering means in the form of a tapered projection 119 guiding the upward movement of the contact member 115 should it become displaced sidewise for any reason.

Preferably, the weight of the arm 112, the contact portion 113, and the contact member 115 is counterbalanced by an arm 120 of the conducting member 111, this arm carrying a weight 121. The counterbalancing effect is such as to maintain the axis of the suspension insulator 110 substantially vertical and to maintain the contact portion 113 near the center of the passage 51 during its vertical movement.

During normal operation, the contact member 115 is in its dotted-line position shown in Fig. 4 to electrically contact the conductor 64 of the bushing, the spring 72 at this time being slightly compressed. When in this position, the upper electrode 20 is energized through the conductor 64, the conducting member 111, and a lead 125 connected to one of the rods 32.

When it is desired to inspect or remove the bushing 42, the transformers are deenergized and the hand wheel 91 is turned to lower the operating member 85, the suspension insulator 110, and the conducting member 111. This moves the contact member 115 from engagement with the resilient contactor 67. Fig. 4 shows the contact member 115 during its retractive movement but it should be understood that such movement is continued until this member clears the gate 58 of the valve 57. At this time the valve can be closed, whereupon the bushing 42 can be removed without drainage of the container 10, or exposure of its contents to the atmosphere, or even without reducing any existing superatmospheric pressure within the container.

It will be understood that the application of the invention to electric treaters is merely exemplary and that the electrodes herein-suggested can be replaced by any other element which it is desired to energize from a high voltage source. Furthermore, while a particular arrangement of parts is herein-disclosed as representative of the preferred embodiment, it should be clear that

various changes and modifications can be made therein without departing from the spirit of the invention as defined in the appended claims.

I claim as my invention:

- 5 1. In a device for attaching an electrical bushing to a container to permit removal and replacement of the bushing without opening said container, said bushing providing a conductor extending therethrough, the combination of: a tubular structure connected to and extending outside said container to provide a passage communicating with the interior thereof; means for connecting said bushing to said tubular structure to extend into said passage; a movable closure for said passage at a position between said bushing and the point of communication of said passage with the interior of said container; a conducting member normally extending along said passage to be in electrical contact with the conductor of said bushing; means for moving said conducting member along said passage a sufficient distance to break electrical contact with said conductor and to clear said movable closure; and means for moving said closure to close off said passage after such movement of said conducting member to permit removal of said bushing from said tubular structure without opening said container.
- 10 2. In a device for attaching an electrical bushing to a container to permit removal and replacement of the bushing without exposing the entire contents of the container to the atmosphere or relieving any pressure differential between the inside and outside of said container, said bushing providing a conductor extending therethrough, the combination of: a tubular structure connected to and extending outward from the top of said container and providing a passage communicating with the interior thereof; means for connecting said bushing to said tubular structure to expose its conductor to said passage; a gate valve for said passage at a position between said bushing and the point of communication of said passage with the interior of said container; an operating member movably extending through the top of said container; a suspension insulator in said container and carried by said operating member to move therewith; a conducting member carried by said suspension insulator to move therewith, said conducting member normally extending along said passage to be in electrical contact with the conductor of said bushing; and means for moving said operating member to move said conducting member along said passage a sufficient distance to break electrical contact with said conductor and to clear said valve whereby said valve may be closed to seal off said passage and permit removal of said bushing.
- 15 3. In a device for conducting high voltage currents into a container through the use of a bushing having a conductor extending therethrough, the combination of: a tubular structure providing a passage communicating with the interior of said container; means for removably connecting said bushing to said tubular structure with said conductor exposed to said passage; a high voltage suspension insulator; means for mounting said suspension insulator to move in said container and for moving said suspension insulator from a position outside said container; and a conducting member carried by said suspension insulator and insulated thereby from said container to move with said insulator, said conducting member providing a contact portion extending into said passage to move into and out of electrical contact

with said conductor of said bushing as said insulator is moved.

4. In a device for conducting high voltage currents into a container through the use of a bushing having a conductor extending therethrough, the combination of: a tubular structure providing a passage communicating with the interior of said container; means for removably connecting said bushing to said tubular structure with said conductor exposed to said passage; a movable closure for said passage; a high voltage suspension insulator; means for mounting said suspension insulator to move in said container and for moving said suspension insulator from a position outside said container; a conducting member carried by said suspension insulator and insulated thereby from said container to move with said insulator, said conducting member providing a contact portion extending into said passage to move into and out of electrical contact with said conductor of said bushing as said insulator is moved, said contact portion moving sufficiently to clear said closure; and means for moving said closure to close off said passage to permit removal of said bushing without opening said container.

5. A combination as defined in claim 4, in which said closure includes a gate valve having a valve member traversing said passage.

6. A combination as defined in claim 3, including a resilient contactor disposed between said conductor and said conducting member and through which electrical contact between these elements is completed.

7. A combination as defined in claim 3, including a resilient contactor disposed between said conductor and said conducting member and through which electrical contact between these elements is completed, said resilient contactor comprising a support member carried by one of these elements, a contact member contactable by the other of these elements when said conducting member is moved, and a spring disposed between said support member and said contact member to be flexed by movement of said conducting member.

8. A combination as defined in claim 3, including a resilient contactor disposed between said conductor and said conducting member and through which electrical contact between these elements is completed, said resilient contactor comprising a support member carried by one of these elements, a contact member contactable by the other of these elements when said conducting member is moved, a spring disposed between said support member and said contact member to be flexed by movement of said conducting member, and means extending between said support member and said contact member to limit the flexure of said spring when said electrical contact is broken.

9. A combination as defined in claim 3, including means for guiding the movement of said suspension insulator to retain said contact portion of said conducting member within said passage and separated from the walls thereof during movement of said insulator.

10. In a device for conducting high voltage currents into a container through the use of a bushing having a conductor extending therethrough, the combination of: a tubular structure providing a passage communicating with the interior of said container; means for removably connecting said bushing to said tubular structure with said conductor exposed to said passage;

first and second suspension insulators in said container, each providing a high voltage terminal; an element in said container supported by said first suspension insulator and electrically connected to its high voltage terminal; means for mounting said second insulator for movement relative to said first insulator and for moving said second insulator from a position outside said container; a conducting member carried by said second insulator in its movement and connected to the high voltage terminal thereof, said conducting member providing a contact portion extending into said passage to move into and out of electrical contact with said conductor of said bushing as said second insulator is moved; and a lead for electrically connecting said conducting member and said element.

11. A combination as defined in claim 10, including a framework in said container carrying said first insulator, said second movable insulator traversing said framework, said means for movably mounting said second insulator including an operating member movably extending from said container and means for sealing said operating member and said container.

12. A combination as defined in claim 3, in which said means for mounting said suspension insulator includes an operating member movably extending through a wall of said container, means for connecting one end of said insulator to said operating member, a stationary guide within said container and positioned to one side of the axis of said operating member, and a guide member carried by and extending sidewise from said operating member to engage said stationary guide and slide therealong during movement of said operating member to prevent turning of said operating member about its axis during such movement thereof and thus guide said contact portion of said conducting member to move within said passage.

13. In combination with a container having a wall: an operating member movably extending through said wall; means for sealing said operating member relative to said wall; means for axially moving said operating member from a position outside said container; a suspension insulator inside said container and providing an end connected to said operating member to move therewith; a stationary guide within said container and positioned to one side of the axis of said operating member; and a guide member carried by and extending sidewise from said operating member to engage said stationary guide and slide therealong during movement of said operating member to prevent turning of said operating member about its axis during such movement thereof.

14. In a device for conducting high voltage currents into a container through the use of a bushing having a conductor extending therethrough, the combination of: a tubular structure providing a passage communicating with the interior of said container; means for removably connecting said bushing to said tubular structure with said conductor exposed to said passage; a high voltage suspension insulator within said container and positioned to one side of the axis of said passage; a conducting member providing an arm attached to said suspension insulator and extending sidewise therefrom, said conducting member including also a contact portion extending from said arm into said passage to be in electrical contact with said conductor of said bushing; and means for moving said suspension

insulator to move said contact portion into and out of electrical contact with said conductor of said bushing.

15. A combination as defined in claim 14, in which said last-named means includes a vertically movable operating member extending from said container, said insulator being hung from said operating member, and including means for counterbalancing said arm and said contact portion to maintain the axis of said suspension insulator substantially vertical during its movement by said operating member.

16. In a device for conducting high voltage currents into a container through the use of a bushing having a conductor extending therethrough, the combination of: a tubular structure providing a passage communicating with the interior of said container; means for removably connecting said bushing to said tubular structure with said conductor exposed to said passage; a high voltage suspension insulator within said container; a conducting member carried by

5
10

said suspension insulator and insulated thereby from said container, said conducting member providing a contact portion extending into said passage to be in electrical contact with said conductor of said bushing; means for separating said conductor of said bushing and said contact portion; and a closure for said passage and comprising a closure member movable across said passage to move between said conductor and said contact portion when separated.
